UNITED STATES PATENT OFFICE.

JAMES MADISON TILLOTSON, OF KINDER, LOUISIANA.

DEEP-WELL PROPELLER-PUMP.

SPECIFICATION forming part of Letters Patent No. 739,746, dated September 22, 1903.

Application filed February 7, 1903. Serial No. 142,304. (No model.)

To all whom it may concern:

Be it known that I, JAMES MADISON TILLOTSON, of Kinder, in the parish of Calcasieu and State of Louisiana, have invented a new and useful Improvement in Deep-Well Propeller-Pumps, of which the following is a specification.

One form of pump for deep wells consists of a vertical shaft bearing propeller-blades and arranged to be rotated so as to cause its propeller-blades to produce an upward flow from said wells. Such long rotating shafts require to be guided at intervals in bearings, and for this purpose boxings have been provided with curved spring-wings extending out from the boxes and adapted to bind against the walls of the well and hold said boxes stationary while the shaft revolves within the same. These spring-wings scrape against the inner walls of the well-tube in being inserted and removed with so much friction as to require a force of one or more tons to force the shaft and its boxings down, and, besides, any roughness on the sides of the well-tube is liable to catch against these spring-wings and damage them.

My invention consists in a deep-well propeller-pump having loose boxings with arms or wings which are smaller than the well-bore and do not touch the sides of the same, except as the shaft may sway or vibrate, and a propeller of a diameter somewhat less than that of the boxing arms or wings, so that in any lateral movement of the shaft the arms of the loose boxing act as fenders against the sides of the well to strike the same and prevent the propeller from coming into contact with said walls, the shaft being freely suspended in the well from its upper end, as will be hereinafter more fully described.

Figure 1 is a vertical section of a well-tubing with deep-well propeller-pump loosely suspended within the same; and Figs. 2 and 3 are details of the guide-boxing, showing two forms of the same in cross-section within the well-casing.

A represents the propeller-shaft, which may be either hollow or solid.

B B are propellers fixed rigidly to the shaft, of which there may be any desired number according to the depth of the well. At the lower end of the well these propellers may be

two and one-half feet apart, while near the upper end of the well they may be five feet apart. Just below each of these propellers is placed one of my loose boxings C, which have straight radial arms or wings c, with terminal flukes c' extending out to about one-fourth of an inch from the well-casing, so that when the shaft is in the center of the casing these arms are perfectly free of the well-casing and with the boxing are capable of turning loosely on the shaft. The propeller is made of a diameter somewhat smaller than the diameter of the boxing-arms, being about one-eighth of an inch less. These loose boxings serve to resist lateral play in the shaft and act as fenders to prevent the propellers from coming in contact with the well-casing, since they are of larger diameter than the propellers.

In forming the guide boxings or fenders the wings may be made separate and bolted or riveted on, as seen in Fig. 2, or they may be cast in one piece with the boxing-sections, as seen in Fig. 3.

The advantages of my improved propeller-pump with loose boxings are, first, the ease with which it will slide down into the well-casing, as it does not bind with any friction against the same; second, there is less friction on the boxings, as they hang loosely on the shaft, the whole weight of the shaft-propellers and wing-boxings being suspended on a ball-bearing collar in the pump-head above ground; third, the cheapness of manufacture, as my guide-boxes can be cast all in one piece, which would make it strong enough, since there is no strain on the same in forcing it down the well, and it supports none of the weight of the shaft, but, on the contrary, the shaft supports it as a fender merely.

Having thus described my invention, what I claim as new, and desire to secure by Letters Patent, is—

1. A rotary shaft for a deep-well pump having one or more rigidly-attached propellers and having also suspended on said shaft near the propeller a loose or freely-swiveling fender-guide of greater diameter than the propeller, said fender-guide being composed of arms or wings disconnected from each other at their outer ends and arranged to hang loose on the shaft and entirely unrestrained,

substantially as and for the purpose described.

2. A rotary shaft for a deep-well pump having one or more rigidly-attached propellers and having also suspended on said shaft near the propeller a loose or freely-swiveling guide-boxing having extended arms or wings disconnected from each other at their outer ends and forming fenders arranged to hang free and unrestrained upon the shaft substantially as and for the purpose described.

3. A deep-well pump comprising a well-casing, a rotary shaft suspended therein and carrying one or more rigidly-attached propellers and having suspended on said shaft a loose and freely-swiveling fender-guide made of smaller diameter than the well-casing but larger diameter than the propeller and arranged to hang free and unrestrained upon

the shaft and normally out of contact with the well-casing substantially as and for the purpose described.

4. A deep-well pump comprising a well-casing, a rotary shaft suspended therein exclusively from the top and carrying one or more rigidly-attached propellers and having loosely suspended on said shaft one or more freely-swiveling fender-guides made of smaller diameter than the well-casing but larger than the propeller and arranged to hang free and unrestrained upon the shaft and normally out of contact with the well-casing substantially as described.

JAMES MADISON TILLOTSON.
